CARTON DISPENSER AND SEPARATOR

Russell E. Matteson, Morris, Ill., assignor to Diamond National Corporation, a corporation of Delaware

Filed Aug. 8, 1958, Ser. No. 753,945
18 Claims. (Cl. 221—9)

The present invention relates to a dispenser and separator for cartons, and more particularly to a dispenser and separator that stores a plurality of groups of nested cartons in a chute, provides for the dispensing of one group of cartons at a time to an access shelf for removal of the cartons individually therefrom, and a control mechanism to prevent the dispensing of a second group of cartons prior to the removal of all of the cartons of the first group from the access shelf.

In modern egg packing rooms, eggs are received from the egg producer in cases that hold thirty dozen eggs each and these eggs are graded and inspected, usually by candling, and then placed in cartons which hold a dozen eggs. In order to achieve economy, the candling and grading of the eggs must be accomplished with great rapidity and to this end equipment has been perfected to enable the candling operation to be swiftly accomplished. However, little attention has been given to the furnishing of the one dozen egg carton to the candler so that the repeated operation of placing the eggs in the carton and then dispatching the carton may be repeatedly accomplished with a minimum of effort and consumption of time.

An object of the present invention is to provide a dispenser for dispensing groups of nested cartons from a chute.

Another object of the present invention is to provide a dispenser for dispensing groups of nested cartons from a chute in which dispensing of a second group is prevented until all cartons of the first group have been removed.

It is yet another object of the present invention to provide a dispenser to accomplish the above objects that is economical to manufacture, comprises a few simple parts, will give reliable service over a long period of rough usage and takes up a minimum amount of space.

Other objects and the nature and advantages of the instant invention will be apparent from the following description taken in conjunction with the accompanying drawings, wherein:

FIG. 1 is a perspective view of an egg carton dispensing mechanism in accordance with the present invention.

FIG. 2 is a cross-sectional view, on an enlarged scale, taken on the line 2—2 of FIG. 1.

FIG. 3 is an enlarged side view of the dispenser of FIG. 1.

FIG. 4 is a view similar to FIG. 3, but showing the parts in another position.

FIG. 5 is an enlarged partial cross-sectional view taken on the line 5—5 of FIG. 3 and looking in the direction of the arrows.

FIG. 6 is an enlarged cross-sectional view taken on the line 6—6 of FIG. 1.

FIG. 7 is a cross-sectional view taken on the line 7—7 of FIG. 6.

Referring now to the drawings, wherein like reference numerals are used to designate like or corresponding parts throughout the several views, there is shown a dispenser 10 comprising a chute 11 for holding the plurality of groups 12 of nested cartons 13. An escapement mechanism 14 is provided to permit a single group 12 of cartons 13 to pass down the chute, escapement mechanism 14 being actuated by the actuating rod 16 which is in turn under the control of the mechanism 17 which is so

2

constructed, as will be explained in detail hereinafter, that only upon removal of all of the cartons 13 of the first dispensed group 12 is it possible to move the control mechanism to actuate the rod 16 and the escapement mechanism 14 through it.

As may be seen in FIG. 1, the groups 12 of cartons 13 are placed in vertically stacked array in the chute 11, and each group 12 comprises nested cartons 13 as is clear from FIG. 2. The cartons 13 are a widely used type of molded pulp egg carton that holds a dozen eggs and that has a bottom section that is compartmented and cellular and has a top hinged at one side and a locking flap hinged at the other side thereof.

The chute 11 is generally rectangular in cross section, as may be seen from FIG. 2, and has an open front 18. Secured to the sides of the chute 11 are a pair of brackets 19, and these brackets 19 extend forwardly of the chute and rotatably support between them a rock shaft 21 that may be seen to extend across the open front 18 and to have secured to it a pair of similar escapement levers 22. As may be seen, the escapement levers 22 extend in a generally vertical plane and have inwardly directed fingers 23 and 23', respectively, at the lower and upper ends thereof. It will be understood that the lengths of the escapement levers 22 and of the fingers 23, 23' depend upon the characteristics of the cartons to be dispensed, and thus may be lengthened or shortened in known manner to meet the requirements of different cartons. A beam 24 is secured to and extends transversely of the escapement levers 22, beam 24 being preferably parallel to the rock shaft 21 and spaced therefrom.

Rotatably suspended from the end of beam 24 is the aforementioned actuating rod 16 that is urged in a clockwise manner as seen in FIG. 1 by the spring 26 that has one end connected to the rod 16 below its connection with the beam 24 and the other end anchored to the chute 11. Spring 26 also exerts a force on the escapement levers 22 to urge them to rotate in a clockwise manner, as seen in FIG. 1, about rock shaft 21. A stop 27 extends from the side of chute 11 and serves as a limiting guide for the actuating rod 16.

It will be understood that movement of the actuating rod 16 downwardly will cause the beam 24 to rotate the escapement levers 22 on the axis of rock shaft 21 so as to bring the lower fingers 23 through the open front 18 of chute 11 while the upper fingers 23' are being removed from their position within the chute. Thus, the group 12 of cartons that are shown held by the upper fingers 23' will be released and caught by the lower fingers 23, and on a subsequent upward movement of actuating rod 16, the opposite rotation of levers 22 will take place to release the lowest group 12 and to retain the next highest group 12.

The control mechanism 17 is shown in FIG. 3 to comprise a handle lever 31 pivotally secured by a bolt 32' at the rear of chute 11. As is apparent from FIG. 1 there is a corresponding lever 31 similarly pivoted on the opposite side of chute 11. Handle levers 31 have upstanding ears 32, see also FIG. 6, and between the ears 32 there extends a handle bar 33. Each of the ears 32 carries a restraining member 34 having a plurality of inwardly extending resilient fingers 35. The restraining member 34 with the fingers 35 is also clearly shown in FIG. 7.

A shelf 37 having an upturned lip 38 extends outwardly from the chute 11, and it is on this shelf, which functions as an access shelf, that the group 12 of cartons 13 comes to rest. The handle levers 31 extend on either side of the group 12, and the fingers 35 of restraining member 34 engage with the edges of the cartons 13 in the group 12 resting on access shelf 37.

Below handle lever 31 there is a downwardly pointing V-shaped lever 41 that is pivoted at a point intermediate

a first leg 42 thereof about a pivot pin 43 extending from the side of the chute 11. The second leg 44 of lever 41 has a handle lever engaging pin 46 extending under the handle lever 31 and is engageable by the underside of handle lever 31 when handle lever 31 is moved to the position shown in FIG. 3.

A ratchet 47 is pivoted at its lower end to the pivot pin 43, and as may be seen from FIG. 5, is between the V-shaped lever 41 and the handle lever 31. A connecting pin 48 extends from the first leg 42 of V-shaped lever 41 into a slot 49 in ratchet 47.

A spring 51 is connected at its lower end to the V-shaped lever 41 at the apex thereof, and extends upwardly to an anchor 52 extending from the side of the chute 11. Preferably, the stop 27 and the anchor 52 are connected to the chute 11 by a single bolt. The spring 51 has a stiffening rod 53 extending therethrough.

Extending outwardly from the handle lever 31 are a stop pin 54 that is forwardly of ratchet 47 and a ratchet pin 55 that is rearwardly of ratchet 47 and engages therewith when ratchet 47 is in the operative position thereof. Also, a hammer 56 extends from the handle lever 31 rearwardly of both the ratchet 47 and the spring 51 with the rod 53 therein. As may be seen from FIG. 5, hammer 56 extends outwardly sufficiently from handle lever 31 to lie in the same vertical plane as the spring 51.

In operation, and assuming that the parts are as shown in FIG. 3, it will be observed that the handle levers 31 are in a lowermost position. There are no cartons on the access shelf 37, so that it is desired to actuate the escapement mechanism 14 to dispense a group 12 of cartons 13 from the chute 11 onto the access shelf 37. To do this, handle bar 33 and handle levers 31 are raised, as by grasping handle bar 33; this action will cause the hammer 56 to strike against the spring 51, and because of the rod 53 therein spring 51 will be caused to rotate about its upper end, fastened to anchor 52, and thus the lower end of spring 51 will describe an arc in a counter-clockwise direction. Because the lower end of spring 51 is connected to the apex of V-shaped lever 41, V-shaped lever 41 will similarly be caused to rotate in a counter-clockwise direction. As V-shaped lever 41 rotates, connecting pin 48 will move to the rear end of slot 49 in ratchet 47, and upon engagement therewith will cause counter-clockwise engagement of ratchet 47, it being understood that both ratchet 47 and V-shaped lever 41 rotate about pivot pin 43. This will bring the parts to the position shown in FIG. 4, and it will be noted that V-shaped lever 41 and spring 51 comprise an over-center mechanism so that the direction of pull exerted by spring 51 is now on the forward side of the pivot pin 43, spring 51 having been thrown there by the force of the blow of hammer 56.

As handle lever 31 is rotated upwardly, or in a counter-clockwise direction, it will engage the lower end of actuating rod 16 and cause it to move upwardly, at the same time maintaining its contact with stop 27 by virtue of the pull of spring 26. As above described, upward movement of actuating rod 16 causes the escapement levers 22, to rock about the axis of rock shaft 21 thus to withdraw the lower fingers 23 of escapement levers 22 from the chute 11 to release a group 12 so that it may fall to the access shelf 37 and be stopped by the lip 38. Meanwhile, of course, the upper fingers 23' have entered through the opening 18 of chute 11 to engage with the next group 12 to retain it from also dropping through the chute 11.

Handle bar 33 is then released when it has gone to the upper limit of its travel, and this is determined by the engagement of ratchet pin 55 in the teeth of ratchet 47 as shown in FIG. 4. Upon release of the handle bar 33, it will be held in substantially the release position by the engagement of the fingers 35 of restraining member 34 with the edges of the cartons 13 that are now on the

access shelf 37. The operator then picks the top carton 13 from the group 12 and the weight of the handle bar 33 and the handle levers 31 cause these parts to rotate about pin 30 and to thus drop down. It will be understood that as successive cartons 13 are removed from the group 12 on access shelf 37, the handle bar 33 and handle levers 31 will rotate in a stepped clock-wise direction. This is due to the engagement of ratchet pin 55 with the teeth of ratchet 47, it being noted that spring 51 is forwardly of pivot pin 43 and thus is urging the V-shaped lever 41 and ratchet 47 (through the pin and slot connection 48, 49) in a counter-clockwise direction.

As the handle lever 31 rotates in its clockwise direction it disengages itself from the actuating rod 16. It is also to be observed that when the handle lever 31 rotates in a clockwise direction as the cartons 13 are being removed from the group 12, spring 26 will exert a pull on the beam 24 to cause the levers 22 to rotate in a clockwise direction so that the lower fingers 23 of the levers 22 enter into the chute 11 to catch and retain the lowest group 12 in the chute 11.

When the last of the cartons 13 of the group 12 on access shelf 37 has been removed therefrom, the underside of handle lever 31 will engage the handle lever engaging pin 46 that extends from the second leg 44 of the V-shaped lever 41, and thus will rotate the V-shaped lever 41 in a clockwise direction (see FIG. 3) about the pivot pin 43. This will cause the spring 51 to move rearwardly of the pivot pin 43 so that the pull of spring 51 urges V-shaped lever 41 in the clockwise direction. Also, connecting pin 48 on the first leg 42 of V-shaped lever 41 will move to the other end of slot 49 in ratchet 47 and upon engagement of that end will also urge the ratchet 47 in the clockwise direction. Movement of both ratchet 47 and V-shaped lever 41 in the clockwise direction is limited by the stop pin 54 that extends from the handle lever 31. This, of course, places the parts back into the position shown in FIG. 3.

It will be seen that there has been provided a dispensing mechanism that is made up of a relatively few easy to manufacture parts, and that takes up a minimum amount of space. This latter advantage, obtains, of course, from the stacking of the cartons 13 on edge rather than placing them flat. Also, the actuation of escapement mechanism 14 is prevented while there are any cartons 13 on the access shelf 37 because the handle levers 31 cannot be raised to actuate the escapement mechanism 14 until it has completed its clockwise travel downwardly and has struck the handle lever engaging pin 46 to rotate ratchet 47 to ratchet release position which is shown in FIG. 3. By virtue of engagement of ratchet pin 55 with the teeth of ratchet 47, together with the urging of spring 51, the handle bar 33 could not be raised while there are still cartons 13 on the shelf 37.

From the above, it will be seen that the dispensing mechanism of the present invention dispenses one group of cartons at a time, and eliminates any possibility of more than one group coming to the access shelf 37 and thus either forcing cartons from the shelf 37 or otherwise disrupting the regular operation of the invention.

Thus, the dispenser of the present invention is easy to operate and is also foolproof in its operation so as to prevent the escapement of more than one group 12 from the chute, and particularly prevents the escapement of a group 12 from the chute while any of the cartons 13 of the previous group 12 are on the shelf 37.

It will be obvious to those skilled in the art that various changes may be made without departing from the spirit of the invention and therefore the invention is not limited to what is shown in the drawings and described in the specification but only as indicated in the appended claims.

What is claimed is:

1. A dispenser comprising a chute for holding a plurality of groups of nested cartons in vertical alignment

and having an open front therein, an escapement mechanism for permitting groups of cartons to pass down said chute sequentially, said mechanism comprising a rock shaft extending across the open front of said chute, at least one escapement lever secured to the rock shaft transversely thereof and having inwardly directed fingers at the ends thereof, means to rock said rock shaft and escapement lever comprising a beam secured to and extending transversely of said lever and spaced from said rock shaft, an actuating rod extending upwardly along the side of said chute and pivotally connected to said beam, a stop on said chute, a spring connected to said chute and said rod and urging said rod against said stop, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, an upstanding ear on each of said handle levers and spaced outwardly of said shelf, a handle bar extending between said ears, a restraining member on the inner side of each ear and adapted to engage the sides of cartons resting on said shelf, said restraining members each comprising inwardly extending resilient fingers, a downwardly pointing V-shaped lever pivoted at a point intermediate a first leg thereof about a pivot pin extending from said chute, a ratchet pivoted at its lower end to said pivot pin and between said V-shaped lever and said handle lever, a connecting pin extending from said first leg of said lever and engaging in a slot in said ratchet, said V-shaped lever and said ratchet movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby cause rotation of said V-shaped lever and said ratchet, upon engagement of said connecting pin and one end of the slot of said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

2. A dispenser comprising a chute for holding a plurality of groups of nested cartons in vertical alignment and having an open front therein, an escapement mechanism for permitting groups of cartons to pass down said chute sequentially, said mechanism comprising a rock shaft extending across the open front of said chute, at least one escapement lever secured to the rock shaft transversely thereof and having inwardly directed fingers at the ends thereof, means to rock said rock shaft and escapement lever, an actuating rod extending upwardly along the side of said chute and operatively connected to said means to rock said rock shaft and escapement lever, a stop on said chute, a spring connected to said chute and said rod and urging said rod against said stop, an access shelf extending from said chute to receive a group of cartons released by said escapement mechanism, a control mechanism at the bottom of said chute for effecting

upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, an upstanding ear on each of said handle levers and spaced outwardly of said shelf, a handle bar extending between said ears, a restraining member on the inner side of each ear and adapted to engage the sides of cartons resting on said shelf, said restraining members each comprising inwardly extending resilient fingers, a downwardly pointing V-shaped lever pivoted at a point intermediate a first leg thereof about a pivot pin extending from said chute, a ratchet pivoted at its lower end to said pivot pin and between said V-shaped lever and said handle lever, a connecting pin extending from said first leg of said lever and engaging in a slot in said ratchet, said V-shaped lever and said ratchet movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby cause rotation of said V-shaped lever and said ratchet, upon engagement of said connecting pin and one end of the slot of said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

3. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, a stop on said chute, a spring connected to said chute and said rod and urging said rod against said stop, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, an upstanding ear on each of said handle levers and spaced outwardly of said shelf, a handle bar extending between said ears, a restraining member on the inner side of each ear and adapted to engage the sides of cartons resting on said shelf, said restraining members each comprising inwardly extending resilient fingers, a downwardly pointing V-shaped lever pivoted at a point intermediate a first leg thereof about a pivot pin extending from said chute, a ratchet pivoted at its lower end to said pivot pin and between said V-shaped lever and said handle lever, a connecting pin extending from said first leg of said lever and engaging in a slot in said ratchet, said V-shaped lever and said ratchet movable between ratchet operative and ratchet release positions, a spring having a rod extending therethrough attached to the V-shaped lever at its apex and extending upwardly to an anchor on the side of said chute, a handle

lever engaging pin extending inwardly from the end of the second leg of said V-shaped and engageable by the underside of one of said handle levers in the lower position thereof to thereby cause rotation of said V-shaped lever and said ratchet, upon engagement of said connecting pin and one end of the slot of said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

4. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, an upstanding ear on each of said handle levers and spaced outwardly of said shelf, a handle bar extending between said ears, a restraining member on the inner side of each ear and adapted to engage the sides of cartons resting on said shelf, said restraining members each comprising inwardly extending resilient fingers, a downwardly pointing V-shaped lever pivoted at a point intermediate a first leg thereof about a pivot pin extending from said chute, a ratchet pivoted at its lower end to said pivot pin and between said V-shaped lever and said handle lever, a connecting pin extending from said first leg of said lever and engaging in a slot in said ratchet, said V-shaped lever and said ratchet movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby cause rotation of said V-shaped lever and said ratchet, upon engagement of said connecting pin and one end of the slot of said ratchet, to ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

5. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, an

access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, a resilient restraining member on the inner side of each handle lever and adapted to engage the sides of cartons resting on said shelf, a downwardly pointing V-shaped lever pivoted at a point intermediate a first leg thereof about a pivot pin extending from said chute, a ratchet pivoted at its lower end to said pivot pin and between said V-shaped lever and said handle lever, a connecting pin extending from said first leg of said lever and engaging in a slot in said ratchet, said V-shaped lever and said ratchet movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby cause rotation of said V-shaped lever and said ratchet, upon engagement of said connecting pin and one end of the slot of said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

6. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, an upstanding ear on each of said handle levers and spaced outwardly of said shelf, a handle bar extending between said ears, a restraining member on the inner side of each ear and adapted to engage the sides of cartons resting on said shelf, said restraining members each comprising inwardly extending resilient fingers, a downwardly pointing V-shaped lever pivoted at a point intermediate a first leg thereof about a pivot pin extending from said chute, a ratchet pivoted at its lower end to said pivot pin and between said V-shaped lever and said handle lever, a lost motion connection between said V-shaped lever and said ratchet, said ratchet being movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby

cause rotation of said V-shaped lever and said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

7. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, a resilient restraining member on the inner side of each handle lever and adapted to engage the sides of cartons resting on said shelf, a downwardly pointing V-shaped lever pivoted at a point intermediate a first leg thereof about a pivot pin extending from said chute, a ratchet pivoted at its lower end to said pivot pin and between said V-shaped lever and said handle lever, a lost motion connection between said V-shaped lever and said ratchet, said ratchet being movable between ratchet operative and ratchet release positions, a spring having a rod extending therethrough attached to the V-shaped lever at its apex and extending upwardly to an anchor on the side of said chute, a handle lever engaging pin extending inwardly from the end of the second leg of said V-shaped lever and engageable by the underside of one of said handle levers in the lower position thereof to thereby cause rotation of said V-shaped lever and said ratchet, to ratchet release position, a stop pin extending from said one handle lever and engageable by said ratchet to limit rotation of said ratchet and said V-shaped lever under the urging of said second mentioned spring and thereby determining the ratchet release position, a ratchet pin extending from said one handle lever and engageable with the teeth of said ratchet when the ratchet is in operative position to thereby prevent upward movement of said handle, and a hammer extending from said one lever and engageable with said second mentioned spring upon raising of said handle to cause the lower end thereof to move to thereby rotate said V-shaped lever and said ratchet about said pivot pin to ratchet operative position.

8. A dispenser comprising a chute for holding a plurality of groups of nested cartons in vertical alignment, an escapement mechanism for permitting groups of cartons to pass down said chute sequentially, an actuating rod extending upwardly along the side of said chute and operatively connected to said escapement mechanism, an access shelf extending from said chute to receive a group of cartons released by said escapement mechanism, a control mechanism at the bottom of said chute for effecting upward movement of said actuating rod, said control mechanism comprising a pair of handle levers pivoted on the sides of said chute at the rear thereof and extending forwardly, one of said handle levers being engageable with said actuating rod in the upper part of its movement to cause it to move upwardly, a resilient restraining member on the inner side of each handle lever and adapted

to engage the sides of cartons resting on said shelf, a ratchet movably mounted on said chute and operatively connected to said one handle lever in one position thereof to prevent upward movement of said handle lever and movable to another position to permit upward movement of said handle lever, means to urge said ratchet into said one position during downward movement of said handle lever as cartons are successively removed from said access shelf, means to move said ratchet to said other position upon removal of all cartons from said access shelf and consequent attainment of said handle lever of a lower position thereof, and means to restore said ratchet to said one position upon raising of said handle lever to move said actuating rod for said escapement mechanism.

15 9. The dispenser of claim 8 wherein said restoring means comprises a spring having a rod extending therethrough.

10 20 The dispenser of claim 9 wherein said restoring means further comprises a hammer operatively connected to said one handle lever and movable thereby and engageable with said spring to move it from one position to another.

11 25 The dispenser of claim 8 wherein said means urging said ratchet into said one position comprises a lever having a lost motion connection with said ratchet.

12 30 The dispenser of claim 11, said ratchet urging means further comprising a spring operatively connected to said lever.

13 35 The dispenser of claim 12, said spring having one end connected to said lever and the other end to said chute, said lever being movable between two positions and said spring passing over the pivotal center of said lever as said lever swings from one position thereof to the other.

14 40 The dispenser of claim 13, wherein said means to move said ratchet comprises elements of said one handle lever and said lever engageable upon attainment of said one handle lever of said lower position thereof to thereby swing said lever.

15 45 The dispenser of claim 13, said spring having a rod therein and said restoring means comprising a hammer operatively connected to said one handle lever and movable thereby and engageable with said spring to move it from one position to another.

16 50 A dispenser comprising a chute for holding a plurality of groups of nested cartons in vertical alignment, an escapement mechanism at an upper level of said chute and operatively connected therewith, said escapement mechanism comprising a vertically extending lever intermediate pivoted on a horizontal axis of rotation exteriorly of said chute, said lever including a pair of coplanar carton-engaging fingers vertically spaced from each other and oscillatable simultaneously in the same vertical plane, one of said fingers being disposed in the path of travel defined by said chute and alternately removable therefrom when the other finger is disposed in said path of travel for permitting one group of cartons to descend in said chute and retaining overlying groups of cartons against descent in said chute until the last of said one group of cartons is dispensed, an access shelf extending from said chute below said escapement mechanism to receive a group of cartons released thereby, actuating means for said escapement mechanism comprising vertically oscillatable, movable means engageable with the uppermost carton on said shelf, means for restraining movement of said actuating means in a direction to actuate said escapement mechanism when at least one carton of a group is on said shelf, and means for deactivating said movement restraining means when said movable means is in a position in which no cartons are on said shelf.

17 55 The dispenser comprising a chute for holding a plurality of groups of nested cartons in vertical alignment, an escapement mechanism at an upper level of said chute and

operatively connected therewith, said escapement mechanism comprising at least a pair of co-planar carton engaging finger means vertically spaced from each other, said finger means being oscillatable in the same plane, one of said finger means being disposed in the path of travel defined by said chute and alternately removable therefrom when the other finger means is disposed in said path of travel for permitting one group of cartons to descend in said chute and retaining overlying groups of cartons against descent in said chute until the last of said one group of cartons is dispensed, an access shelf extending from said chute below said escapement mechanism to receive a group of cartons released thereby, a member movably mounted on said chute, means on said member engageable with the uppermost carton on said shelf for establishing the position of said member, means engageable by said member for actuating said escapement mech-

anism, and means restraining movement of said member in a direction to operate said engaging means only when said carton engaging means on said member locate said member in a position in which no cartons are on said access shelf.

18. The dispenser of claim 17, and means for deactivating said movement restraining means when said member is in position established by an absence of cartons on said access shelf.
